UNITED STATES PATENT OFFICE.

VICTOR E. BEAGLE, OF ALEXANDRIA, VIRGINIA.

HOISTING TRUCK.

Application filed December 27, 1922. Serial No. 609,282.

To all whom it may concern:

Be it known that I, VICTOR E. BEAGLE, a citizen of the United States, residing at Alexandria, State of Virginia, have invented certain new and useful Improvements in Hoisting Trucks, of which the following is a specification.

This invention relates to improvements on trucks of the general type set forth in my Prior Patents No. 1,186,976, June 13, 1916, and No. 1,437,583, December 5, 1922, and has for an object to provide means of a desirable character, cooperative with a hoist for supporting a load. It is a further important object of the invention to provide means on the load supporting element which will, by movement into load supporting position, lock the rear end portions of a U-shaped frame in such manner that they will be mutually connected and supported, and liabilities of distortion of the frame reduced to a minimum. It is also an important aim to provide a novel form of travelling carriage on a truck frame of this type, with the aim of attaining the locking of the side members therein in a simple manner. It is a further aim to improve the travelling carriage element in the specific means for connecting a cross bar thereto upon which a load may be supported.

Additional objects, advantages and features of invention are involved in the construction, arrangement and combination of parts, as may be understood from the specific description of the embodiment of the invention herewith, and from the drawings, in which,

Figure 1 is a side elevation of a truck constructed in accordance with my invention;

Fig. 2 is a cross section thereof looking toward the rear;

Fig. 3 is a cross section of one side member of the frame, showing the mounting of the rear truck thereon;

Fig. 4 is a horizontal sectional view on the line 4-4 of Fig. 1;

Fig. 5 is a top view of one rear end of the frame;

Fig. 6 is a bottom view of one of the rear truck units, with my locking device engaged therewith, the cross bar being broken away;

Fig. 7 is an elevational view of the means

for moving the carriage members, the frame and hoist bar being omitted, except as directly involved.

Fig. 8 is a detail cross section of the frame illustrating the buffer bar and support, 60

Fig. 9 is a side elevation of a modified form of truck,

Fig. 10 is a reduced top view thereof,

Fig. 11 is a front elevation thereof,

Fig. 12 is a detail section of the rear wheel mounting,

Fig. 13 is a detail cross section illustrating the load supporting member and carriage element,

Fig. 14 is a side view of the spindle 70 casting,

Fig. 15 is a fragmentary cross section illustrating a further form of mounting for the rear wheels,

Figs. 16 to 20 inclusive, illustrate the 75 various stages of operation, in elevating a load by the use of my truck.

There is illustrated a truck including a frame 10 which has been customarily formed of a U-shape, as indicated in my above mentioned patents, the side members 11 of the frame being entirely without any connection from their rear ends, to a point closely adjacent the front end of the truck. The frame is supported at its forward end by 80 a wheel 12 mounted so as to be turned by a tongue 13 for steering of the truck. A means is shown at 14 for elevating the forward end of a body or load to be carried upon the truck, when the truck is backed into position therearound, this including the hoisting device 15 movable vertically midway of the members 11 at the forward part on the frame. The hoisting mechanism 14 in the present instance does not comprise 85 an essential of the invention to be presented herein and other hoisting devices may be employed, if and as found suitable. The rear ends of the members 11 are supported upon wheels 16, carried in U-shaped yokes 17, the bights of which are flattened and receive the members 11 thereon, the yoke and side members being bolted together, as shown.

Movable longitudinally upon each side member, there is a carriage element 18, and the two are moved together, by respective chains 19 which are extended around re-

spective guide wheels 20 at the rear ends of the side members, and around sprockets 21 at the front part of the frame, the sprockets being keyed upon a transverse shaft 22, 5 mounted revolubly at the lower side of the frame, and having an intermediate sprocket 23 driven by a corresponding sprocket 24 on the shaft 25 which is provided with a hand crank 26, a chain 27 transmitting motion between the two last named sprockets. It is understood that the chain 19 is secured to the carriage in any suitable manner, so that movement of the crank in one direction will move the carriage forward, and reverse 10 operation of the crank will move it rearwardly.

Each carriage comprises an upper box portion 27, open at the front and rear and of substantially rectangular form, being of a dimension to receive loosely the members 11, 20 these members being shown as channel members with side flanges projected downwardly. The box extends sufficiently above the side member to permit the mounting of box- 25 supporting rollers 28 transversely therein on shafts 29 which are extended through the box. The rollers are of a size to be entirely enclosed within the box, so that they will not become fouled nor have clothing 30 or objects entangled therein, readily. The side members of the box 27 are extended downwardly and inwardly a distance beneath the side members 11, as at 30 and then are extended vertically downward as at 31 35 in parallel relation a distance, their opposed faces being suitably channelled or grooved and raised to receive therein and properly engage in respective sides of a cross bar 33 of channel iron, the ends 32 of which are 40 projected upwardly between the members 31 of respective carriages and extended horizontally for the full width of the truck, a short distance above the ground level, although the form and height of this bar may 45 be varied as desired. The ends 32 and members 31 are secured together by means of heavy bolts 34. The wheel yokes 17 are shown to have their forward edges slightly inclined and a rear edge inclined in a 50 greater degree, thus affording a wide bearing beneath the side members of the truck frame and insuring rigidity of this yoke with respect to the side members, by reason of the large number of rivets or bolts which 55 it is possible to use in its attachment. It is not essential that the forward edge of the yoke be inclined, necessarily, and this may be varied as desired.

Each carriage member is formed with 60 wing plates 35, which extend rearwardly from the members 31, and are also joined integrally to the parts 30 and the lower parts of the sides of the box 18. The wing members are formed in such manner that 65 when the carriages are at the rear limit of

their movement, the side members of the yokes 17 are snugly engaged between the wings 35 and held securely against relative lateral movement with respect to the carriages. The carriages are securely fixed 70 upon the cross bar 33, and there is thus formed a mutual rigid connection between the yokes which in itself also insures their retention by its own strength, in fixed relative relation. The wings 35 are shown to 75 have a slight taper toward the rear on the inner side, so as to facilitate entry of the yoke 17 therebetween, and they are also shown slightly thicker at the bottom than at the top, as may be seen in Fig. 4, so that 80 snug fitting engagement with the yoke 17 will be insured. The taper and thickening however, may be varied or dispensed with, as found desirable.

In the use of this form of device, in order to place a load upon the truck, the crank 26 is operated while the member 15 is elevated, to bring the cross bar 33 to its forward position, illustrated in dotted lines in Fig. 1. This will permit a truck to be 85 backed into position with the side members extending on opposite sides of the load to be carried, and the member 15 may then be lowered, and the truck pressed rearwardly to engage the member 15 beneath the forward end of the load. The hoisting device is then operated to elevate the forward end of the load, after which the crank 26 is operated to move the bar 33 rearwardly beneath the load, preferably to the position 90 shown in full lines in Fig. 1, where it will lock with the yokes 17, after which the member 15 is lowered, the load engaging upon the bar 33, and its rear end being finally elevated. When the full clearance is 95 attained, the truck may be moved with its load thus carried.

The use of this form of mounting for the bar 33 obviates the necessity for very heavy construction of the side members 11 throughout the major part of their length. It supports the rear wheels against tendency to 110 twist the frame members 11 when the truck is positioned crosswise on a slope, and also prevents similar strains from detrimentally 115 affecting the truck when lateral vibrations are communicated thereto for any reason.

It will be apparent from the foregoing that a simple construction is provided, which nevertheless may be used for carrying very heavy loads with a minimum of time required for loading, and a small element of wear.

The mounting of the wheels in the yokes 17 includes an axle 36 in each yoke. The 125 axle projects at its inner end and has inserted therethrough the rear end of a tension and buffer rod 37, which extends forwardly to a rest 38, the upper part of which 130 serves as the mounting for the shaft 22.

carrying the forward sprockets 21. From the rest the rod is extended forwardly and upward and is secured in an anchorage 39 on the underside of the truck frame. Rearwardly of the rest 38 this rod lies just inwardly of the path of the carriage 18, and insures the proper positioning of the truck when being backed into position for loading, so that when the carriage is moved rearwardly it will not strike the load and be blocked.

The mounting of the load sustaining element may be constructed to truss the side members of the frame in other ways, and in Figures 9 to 14 inclusive there is illustrated a heavy duty trailer truck in which the particular construction of the first form might not be suitable. In this instance, the frame side members 40 are truss elements including top and bottom stringers 41 connected by diagonal flats 42. Adjacent the rear end at each side a heavy fitting 43 is secured between the two stringers having oppositely projected stub axle shafts 44 upon which respective wheels 45 are mounted at the inner and outer sides of the member 40 respectively. At the rear ends of the frame, hangers 46 are provided depending and adapted to receive a removable load supporting bar 47 insertible therethrough.

At the forward end of this truck an arch 48 of channel iron is provided having its side members bolted to the outer sides of the frame just a little back of the extreme forward end of the frame. This arch is braced by diagonals 49 from the front cross member of the frame. A chain hoist 50 is mounted centrally of the arch which may be used to lift the forward end of the load.

The lower stringer 41 of the frame is inclined upwardly at the forward end, as shown in Figs. 9 and 11, and the entire side member at this part is curved inwardly, as shown in Figs. 10 and 11. This construction gives ample clear way under the frame at the forward part for the mounting of comparatively large front wheels 51 which may be carried in a dirigible mounting 52 following any approved construction. The mounting includes a forwardly projecting draft tongue 53 by which the truck may be towed. Other construction and other means for moving the truck may be adopted readily.

It should be noted that the wheels 45 are spaced sufficiently from the side members of the frame to permit the carriages 54 of a load support 55 to pass therebetween. The load supporting member comprises a channel member hung from the carriages, which comprise flat plates bent to form a snug boxing for the respective side members 40. The boxing extends sufficiently above the frame to accommodate rollers 56, as seen in Fig. 13. The member 55 may be moved

by an adaptation of the means before described for shifting the load carrying element, or other means may be employed.

In Fig. 15 another embodiment of the heavy duty truck is illustrated, in which upper and lower elements are combined in the side members of the frame, in a slightly different manner, and single wheels are mounted outward of each side of the frame.

In this instance, I have illustrated a method of mounting the side members of the frame in such manner that the load carrying bar may be moved rearwardly past the wheel truck members, and this may be accomplished whether there is one or two longitudinal structural elements in each side member of the frame. In the present instance, there are illustrated two longitudinal I-beams 60 comprising the side members of the frame, carried upon spindle castings 61, mounted in heavy rubber tired wheels 62 which may be of any usual construction. The spindle forgings including an upper inwardly extending bracket 63, upon which one beam 60 is mounted, and over which a bracing arm 65 is provided, against which the web of the beam 60 is secured. Beneath the bracket 63 a downwardly extending arm 66 is formed on the spindle member at the lower end of which a bracket 63' is provided, over which there is a brace 65' to which the lower beam 60 is secured, as shown. The arm 66 is proportioned and inclined so that there is a clearance between it and the upper part of the beam 60, and the forging is also proportioned to receive the two beams with a sufficient clearance from the wheel 62. Carriage elements 67 are formed integrally with a load carrying bar 33', as shown, although these parts may be separately constructed if desired. The carriage elements have two similarly formed outwardly projected brackets 68, one over each of the beams 60, and including downward projected parts within which are mounted rollers 69, the brackets 68 engaged under the upper outer flanges of the beams 60 whereby secure and rigid relation is established between the carriage elements and the side members of the truck frame. In this way, the torque developed by a load, tending to incline the wheels 62 inwardly toward the top, is resisted by the carriage element and cross bar 33'.

For a ready understanding of the manner of use of this truck Figures 16 to 20 are presented, and the operation described applies to all forms of the truck. A load being upon the ground, the truck is drawn to a position with the load in line with and adjacent the rear open end of the frame. The load carrying element being moved to the forward limit of its movement upon the frame, it is backed into position as in Fig. 17. Such hoist device as may be employed

is then engaged with the forward part of the load and it is hoisted as shown in Fig. 18 until the load carrying element may be moved rearwardly of the center of gravity 5 of the load, and preferably to its rearmost position, as in Fig. 19. The forward end of the load is then lowered, when its intermediate part will be brought into bearing upon the load support, and pivoting there 10 the rear end will rise. The load is in this way adjusted so as to clear the ground properly and the truck then moved with the load thereon.

What is claimed:—

- 15 1. In a truck of the character described, a truck frame proper, a load supporting member movable thereon, said frame having wheel mountings thereon at opposite sides, said load supporting member and wheel 20 mountings having parts operative to interlock when the load supporting member is in load supporting position.
- 25 2. The device of claim 1, in which the wheel mountings include parts below the frame, and the load supporting member includes parts slideable on the side members of the frame and connected by a rigid member, and having projected parts to receive and engage positively against lateral movement, 30 the said parts of the wheel mounting below the frame.

3. The device of claim 1, in which the load supporting member includes carriage elements on the side members of the frame and a connecting rigid member, the wheel 35 mountings include vertical members, and the carriages have rearwardly projected wing flanges spaced and disposed to snugly and positively receive and engage the vertical members against relative lateral movement. 40

4. In a truck of the character described, a U-shaped frame, wheel mountings at the rear of each side member including vertical members rigidly fixed upon the frame, carriage elements slideable longitudinally on the 45 frame having a rigid connecting bar therebetween and fixed thereto, said carriage elements having rearwardly projected plates spaced to firmly receive and engage therebetween the said vertical members to prevent 50 relative movement thereof.

5. In a truck, an open ended frame, supporting wheels and mountings therefor, a longitudinally movable load carrying element on the opposed members of the frame 55 constructed and arranged to form a rigid truss between the wheel mountings at opposite sides of the truck adjacent the open end of the frame.

In testimony whereof I have affixed my 60 signature.

VICTOR E. BEAGLE.
